(57) **CLAIM**

The ornamental design for backplane for an industrial control system (ICS), as shown and described.

DESCRIPTION

FIG. 1 is a first isometric view of a backplane for an industrial control system (ICS);

FIG. 2 is a top plan view of the backplane for an industrial control system (ICS) of FIG. 1;

FIG. 3 is a first side elevation view of the backplane for an industrial control system (ICS) of FIG. 1;

FIG. 4 is a first end elevation view of the backplane for an industrial control system (ICS) of FIG. 1;

FIG. 5 is a second side elevation view of the backplane for an industrial control system (ICS) of FIG. 1;

FIG. 6 is a second end elevation view of the backplane for an industrial control system (ICS) of FIG. 1;

FIG. 7 is a bottom plan view of the backplane for an industrial control system (ICS) of FIG. 1; and,

FIG. 8 is a second isometric view of the backplane for an industrial control system (ICS) of FIG. 1.

The broken lines in the drawings illustrate portions of the backplane for an industrial control system (ICS) which form no part of the claimed design.
